Primary Examiner — Ian Simmons*Assistant Examiner* — Dana L Meyrow(74) *Attorney, Agent, or Firm* — Abelman, Frayne & Schwab(57) **CLAIM**

The ornamental design for an alcoholic beverage bottle, as shown and described.

DESCRIPTION

FIG. 1 is a front view showing my alcoholic beverage bottle design;

FIG. 2 is a top plan view thereof; and,

FIG. 3 is a bottom plan view thereof.

The broken lines in the drawings illustrate the portions of the design that form no part of the claim.

1 Claim, 2 Drawing Sheets*FIG. 1*

FIG. 2

FIG. 3
